United States Patent

Des. 235,282
Patented June 3, 1975

235,282

YARN CONE

Charles Robert Langston, Jr., Seneca, S.C., assignor to
Coats & Clark, Inc., New York, N.Y.

Filed Sept. 4, 1973, Ser. No. 393,968

Term of patent 14 years

Int. Cl. D15—06

U.S. Cl. D92—15

FIG. 1.

FIG. 2.

FIG. 3.

FIG. 4.

FIG. 1 is a perspective view of a yarn cone showing my new design, taken from the front with the upper end slightly tilted forwardly to show the top thereof, the ridges encircle the cone and all sides are identical to that shown;

FIG. 2 is an enlarged cross sectional view through the side of the cone, the portion shown broken away being similar to the portion shown;

FIG. 3 is a top plan view of FIG. 1; and

FIG. 4 is a bottom plan view.

I claim:

The ornamental design for a yarn cone, as shown and described.
